UNITED STATES PATENT OFFICE.

LOUIS SPIRLIN, OF NEW YORK, N. Y.

CUSHION-INSOLE.

1,213,965.

Specification of Letters Patent. Patented Jan. 30, 1917.

Application filed October 20, 1915. Serial No. 56,909.

To all whom it may concern:

Be it known that I, LOUIS SPIRLIN, a citizen of the United States, and a resident of New York, county and State of New York, have invented a certain new and useful Improvement in Cushion-Insoles, of which the following is a full, clear, and exact specification.

This invention relates to a class of devices adapted to be used in conjunction with foot-wear.

My invention has for its object primarily to provide an insole designed to be employed interiorly of the shoe, and other forms of the footwear of persons whereby the arch, or shank of the wearer's foot may be comfortably supported in the shoe as well as tending to cause the pressure to be directed centrally of the foot when the person is walking, and the insole also being of a form serving to fill-out the portion of the upper of the shoe above the shank of its sole so that the shoe will fit snugly as this part of ordinary makes of shoes are invariably cut so full that the wearer frequently suffers considerable discomfiture.

The invention consists essentially of a flexible bottom member, or layer of a shape conforming with the shape of the inner surface of the sole of the shoe, and on this bottom layer is a top flexible member, or layer formed with a substantially semi-elliptic projecting portion overhanging the shank part of the bottom layer. Between the layers of the insole is an approximately elliptic resilient pad which also overhangs the shank part of the bottom layer, and the top surface of this pad is in contact with the underside of the overhanging portion of the top layer to serve as a cushion for the arch of a person's foot.

Another object of the invention is to bevel the edge of the pad under the overhanging portion inwardly toward the bottom layer so as to conform with the part of the upper of the shoe above the shank of the sole.

A further object of the invention is to provide a cushion insole which may be made in any shape and size for use in conjunction with footwear of various shapes and sizes.

A practical embodiment of the invention is represented in the accompanying drawing forming a part of this specification in which similar characters of reference indicate corresponding parts in all the views, the said invention being more fully described herein-

after, and then pointed out in the claim at the end of the description.

In the drawing, Figure 1 is a fragmentary view, showing a person's foot disposed in a shoe with one form of cushion insole embodying my invention applied thereto. Fig. 2 is an enlarged top plan of the insole. Fig. 3 is an enlarged inverted plan of the insole, and Fig. 4 is a section taken on the line IV—IV of Fig. 2.

The cushion insole has a bottom member, or layer 10 which may be made of leather, or any other flexible material, and this layer is formed so as to conform with the shape 70 of the inner surface of the sole, as 11, of a shoe, as 12, or a boot, or other type of foot-wear made to be worn by a person, though the shank part 13 of the bottom layer may be formed somewhat narrower in width 75 than the shank of the sole of the shoe.

On the bottom layer 10 of the insole is a top member, or layer 14 which may also be made of leather, or any other flexible material, and this top layer may be made of a size and shape conforming with only the heel and shank portions of the bottom layer, as shown, or the top layer may be made of a size and shape corresponding to that of the bottom layer in entirety. The top layer 14 85 has a substantially semi-elliptic portion, or curved extension 15 projecting laterally from its shank portion 16 so as to overhang the shank part 13 of the bottom layer 10, and part of the edges of the top layer and bottom 90 layer may be secured by stitching, as at 17, or by any other means, in order to provide a pocket 18 between the opposed shank portions of the bottom and top layers.

Disposed in the pocket 18 between the 95 flexible bottom layer 10 and the flexible top layer 14 is a pad 19 which may be made of rubber, or other resilient material to serve as a cushion for the arch, or shank portion of a person's foot. The cushion, or pad 19 is approximately elliptic in shape. This pad is of a width to extend from substantially midway of the shank portions of both layers of the insole to the free edge of the semi-elliptic projecting portion 15 of the top layer 14, 100 and the pad is of a length similar to the lengths of the shank parts of the layers 10 and 14. The resilient pad will thereby contact with the underside of the semi-elliptic overhanging portion 15 of the top layer 14 so 105 as to also overhang the shank part of the bottom layer 10. The top surface of the

resilient pad 19 is formed on an incline, as 20, from the free edge of its overhanging portion toward the opposite edge thereof, this second edge being preferably graduated 5 to nothing, and the pad is secured in the pocket 18 by stitching, or otherwise fastening its graduated edge to the top and bottom layers of the insole, as at 21. As illustrated in Fig. 1, by forming the resilient pad 19 in 10 this manner the insole will serve when in use to comfortably support the arch of the foot 22 of a person as well as tending to cause the pressure to be directed centrally of the foot when the person is walking, and serving to 15 fill-out the portion of the upper of the shoe above the shank of its sole. The edge of the cushion, or pad 19 under the semi-elliptic portion 15 of the top layer 14 is beveled inwardly, as at 23, toward the bottom layer 10 20 of the insole, thus forming a flexible side portion capable of bending upwardly and readily following the contour of the shoe upper when lacing the shoe, to draw the projecting portion of the pad into firm contact 25 with the inner side of the arch above the shoe sole, thus supporting the arch both on the bottom thereof and at the inner side, where there is always a loose play between the shoe and the foot, and positively preventing all 30 sagging of the arch. The bevel edge 23 of the pad will then cause this part of the shoe to fit snugly as well as producing a neat appearance to the shoe as this part of the ordinary makes of shoes are invariably cut so 35 full that the wearer frequently suffers considerable discomfiture.

In the foregoing description, I have embodied the preferred form of my invention, but I do not wish to be understood as limiting myself thereto, as I am aware that modi- 40

fications may be made therein without departing from the principle, or sacrificing any of the advantages of this invention, therefore I reserve to myself the right to make such changes as fairly fall within the scope 45 thereof.

Having thus described my invention, I claim as new and desire to secure by Letters Patent:—

In a cushion insole for footwear, a flexible 50 bottom layer of a shape conforming to the shape of the inner surface of the sole of the footwear, a flexible top layer on the bottom layer having an uninterrupted upper surface and formed with a substantially semi-elliptic 55 projection overhanging the shank part of the bottom layer, and parts of both of the layers being connected together but having free outer edges, thereby providing an open pocket between the shank parts thereof, and a rubber pad secured in the pocket and disposed under the overhanging projection of the top layer, the said pad being formed with a top surface inclined downwardly to- 60 ward the central parts of the layers, and the edge of the pad under the overhanging projec- 65 tion of the top layer being beveled inwardly toward the lower layer, said pad being adapted to have its underhanging por- 70 tion bend upwardly to follow the contour of the interior of the shoe adjacent the inner side of the wearer's arch, substantially as set forth and for the purpose specified.

This specification signed and witnessed this nineteenth day of October A. D. 1915. 75

LOUIS SPIRLIN.
